DESIGN FOR A CORRESPONDENCE PORTFOLIO

Irving Weinger, Brooklyn, and Samuel Widder,
New York, N. Y., assignors to J. Widder & Co.,
New York, N. Y., a corporation of New York

Application December 29, 1942, Serial No. 109,162

Term of patent 7 years

To all whom it may concern:

Be it known that we, Irving Weinger and Samuel Widder, citizens of the United States and residents, respectively, of Brooklyn, in the county of Kings, city and State of New York, and New York, in the county, city, and State of New York, each with a post-office address in care of J. Widder & Co., 110 Fifth Avenue, New York city, New York, have invented a new, original, and ornamental Design for a Correspondence Portfolio, of which the following is a specification, reference being had to the accompanying drawing, forming part thereof, in which:

The bottom faces of our correspondence portfolio, opposing those shown in Figure 2, are plain, the connected panels, reading from left to right, are adapted respectively to provide a photograph frame, a holder for writing paper or the like, a holder for a blotter or the like, and a series of indexed leaves or the like.

We claim:

The ornamental design for a correspondence portfolio, as shown and described.

IRVING WEINGER.
SAMUEL WIDDER.
